FIG. 5 Inventor
P. Elphick

By *John J. Elphick*
his Atty.

UNITED STATES PATENT OFFICE.

PERCY ELPHICK, OF BALCOMBE, ENGLAND.

MEANS FOR WARMING THE RADIATORS OF MOTOR CARS

Application filed April 26, 1921. Serial No. 422,222

To all whom it may concern:

Be it known that I, PERCY ELPHICK, a subject of the United Kingdom of Great Britain and Ireland, and resident of ⁵ Neads, Balcombe Place, Balcombe, in the county of Sussex, England, have invented certain new and useful Improvements in Means for Warming the Radiators of Motor Cars, of which the following is a specification, such as will enable others skilled in the art to which it appertains to make and use the same.

This invention relates to improved means for preventing the freezing of water in the ¹⁰ radiators and engine water jackets of motor cars and the like by a simple means capable of being used in practically all cases where an ordinary electric service is installed.

²⁰ It is well known that if the water in radiators and engine water jackets of motor cars is not kept from freezing in cold weather very serious results may occur and it is also a distinct advantage to keep the water ²⁵ warm considerably above freezing point at all times.

Owners of motor-cars often experience considerable difficulty in maintaining the desired heat of the water when the car is ³⁰ standing in a garage or other place for a considerable time and in a general way the method adopted for maintaining the heat is to warm the whole garage as by using stoves, hot water and other radiators.

³⁵ The installation and upkeep of apparatus of this kind is pretty costly and my invention is designed for the purpose of providing a simple, inexpensive and efficient means of attaining the same end when the garages or ⁴⁰ other places are furnished with electric current.

Briefly, my invention consists in providing an electrically heated apparatus which can be attached to an ordinary lampholder, ⁴⁵ plug, socket or other fitting and which can be applied to some part of the radiator or its connections and will impart to the same sufficient heat to keep the water warm.

A simple form of the apparatus comprises ⁵⁰ a cylindrical tube which I will call the shell, sealed at both ends but having at one end a connection such as a nipple by which it can be connected to the motor car radiator, say in place of the usual draw-off tap and ⁵⁵ with or without a small draw-off tap. The connection is such that water can flow from

the radiator into the shell. Concentrically within this shell is a tube in which an electric resistance is placed and to which a socket or other electric wire-carrying means can ⁶⁰ be applied in such a manner that when the current is on the resistance is heated and rapidly raises the temperature of the water between the shell and the central tube, the said heat being communicated to the whole ⁶⁵ of the water in the radiator and water jackets of the engine.

In another form the heater can be applied to the pipe between the radiator and the water jacket on the engine, or it may be ⁷⁰ made to clamp externally onto the radiator or be otherwise applied so that the heat of the element in the device is conducted or conveyed to the water of the radiator or water jacket to maintain same above freezing point. ⁷⁵

I have found by experiment that if the water enters the heating device or apparatus it is not generally necessary to construct the device on a flow and return principle ⁸⁰ but that simple, plain tube connections between the water in the shell and the water in the radiator is sufficient. The apparatus may have a small draw-off tap which can be momentarily opened so that air in the ⁸⁵ shell will be expelled by water flowing in from the radiator.

Examples of my invention are shown in the accompanying drawing in which

Fig. 1 illustrates a heater, partly in section, suitable for connecting to a radiator at the point where a draw-off tap is often fitted. ⁹⁰

Fig. 2 shows a radiator with a heater, such as is seen in Fig. 1, fitted to it, the said heater having a small draw-off tap. ⁹⁵

Fig. 3 shows a modification in which the heater is of T shape and suitable for attachment between the radiator and the engine in the usual flow-pipe which in a general way has an indiarubber tube connection. ¹⁰⁰

Fig. 4 illustrates a radiator with an external heater clamped to it.

Fig. 5 shows another form of heater of ¹⁰⁵ different external shape but suitable for much the same connection as that shown in Fig. 3.

Fig. 6 shows the heater seen in Fig. 5 but on reduced scale connected between a ¹¹⁰ radiator and an engine.

In Fig. 1 the device comprises a shell 1

with nipple attachment 2 adapted to screw into the tap hole of a radiator as is seen in Fig. 2. Within the shell 1 is a tube 3 lined with mica or other suitable material 5 and containing a heating element 4 to which electric connection can be made at the holder 5. Water from the radiator will pass into the annular space 6 between the tube and the shell and will be heated sufficiently to 10 maintain the temperature of the water in the radiator and water jackets at the required point.

In Fig. 2 the radiator 7 has a heater 2, like that shown in Fig. 1, fitted to it, the said heater having a small draw-off or pet cock 8.

The heater seen in Fig. 3 is much like that shown in Fig. 1 but instead of a nipple tube has a larger cross tube 9 which can be connected by two rubber sleeves, of which one, 10 is seen, to a pipe between the radiator and the water jacket of the engine.

In Fig. 4 a substantially rectangular heater 11 having any suitable electric element is 25 seen held by clamps 12 and thumb screw 13 to the edge of a radiator 14. In Fig. 5 the heater 15 is of cylindrical form and has pin contacts 16; the element is not shown but it must be understood to be arranged inside the 30 heater in any suitable way. This heater 15 is seen on smaller scale in Fig. 6 fitted between the radiator 17 and the water jacket 18 of an engine.

It will be evident that my invention can 35 be carried out in a large number of ways within the scope of the following claims and that the drawings are examples only of some of the forms the invention may take.

What I claim as my invention is:

40 1. A heater for automobile radiators, com-

prising a tubular casing adapted to have one end secured to the radiator, a tube closed at one end adapted to fit within the casing and formed with an annular base portion having threaded engagement with the other end 45 of the casing and providing an annular water space around said tube communicating with the radiator, and a heating element adapted to be removably inserted into said tube.

2. A heater for automobile radiators, comprising a casing adapted to have one end engaged and communicating with the radiator, a closure for the other end of the casing having a tube projecting therefrom 55 into the casing and closed at the end, an insulating covering for the interior of the tube, and an electric heating element removably inserted in said tube.

3. A heater for automobile radiators, 60 comprising a tubular casing having one end secured to the radiator and communicating with the interior thereof, an annular cap member secured to the other end of the casing, a tube opening through the cap and 65 carried thereby extending within the casing and concentrically disposed therein, the end of the tube within the casing being closed, an electric heating element extending within the tube and removably secured to the 70 cap, and a socket connection adapted to receive a plug for connecting the heating element with a source of electrical energy.

In witness whereof I have hereunto set my hand in presence of two witnesses.

PERCY ELPHICK.
